EX
OR D 7,382

EXAMINER'S ROOM.

No. 7,382

Apr. 21-1874.

UNITED STATES PATENT OFFICE.

CALVIN L. BUTLER, OF GREENFIELD, ASSIGNOR TO THE JOHN RUSSELL CUTLERY COMPANY, OF TURNER'S FALLS, MASSACHUSETTS.

DESIGN FOR CUTLERY-HANDLES.

Specification forming part of Design No. 7,382, dated April 21, 1874; application filed April 4, 1874.
[Term of Patent 7 years.]

A.

To all whom it may concern:

Be it known that I, C. L. BUTLER, of Greenfield, Franklin county, Massachusetts, have invented a Design for Cutlery-Handles, of which the following is a specification:

The nature of my design is fully represented in the accompanying drawing, to which reference is made.

A represents the handle, which is tipped at the end portions with bright metal or plated metal, and in each tip is a rectangular figure, B and C, corresponding to the surface of the handle which is left uncovered by the tip.

I claim as my invention—

A design for a knife-handle or other article of cutlery, consisting of tips on the end portions of bright or plated metal, in the form shown in the drawing, inclosing a rectangular figure, B and C, substantially in the manner described.

CALVIN L. BUTLER.
